UNITED STATES PATENT OFFICE

91,323

DESIGN FOR A TIRE OR SIMILAR ARTICLE

John F. Jones, Brookline, Mass., assignor to The Pharis Tire and Rubber Company, Newark, Ohio, a corporation of Ohio

Application November 2, 1933. Serial No. 49,634

Term of patent 14 years

To all whom it may concern:

Be it known that I, JOHN F. JONES, a citizen of the United States, residing at Brookline, in the county of Suffolk and State of Massachusetts, have invented a new, original, and ornamental Design for Tire or Similar Article, of which the following is a specification, reference being had to the accompanying drawing, forming a part thereof.

Fig. 1 is a perspective view of a tire or similar article, only a section thereof being presented in full lines, showing my new design.

Fig. 2 is a transverse sectional view taken therethrough.

I claim:

The ornamental design for a tire or similar article, as shown.

JOHN F. JONES.
